SHOE

Warren L. Delaney, Lewiston, Maine

Application July 9, 1936, Serial No. 89,835

2 Claims. (Cl. 12—142)

My invention relates to shoes and one of the objects is the production of a shoe that has the good wearing qualities and flexibility of a sewed shoe and the smart lines and dainty, yet sturdy, character of a cemented shoe.

In a shoe, where the sole is cemented to the upper from heel to toe, there is a chance of the sole coming off the shoe, particularly around the forepart of the shoe. Then again, there are objections to a cemented sole, because it is claimed that it burns the feet of the wearer.

In the manufacture of a sewed shoe, when channeling the shank of the outersole and then sewing down the shank, the shoe becomes distorted and takes away from the shoe-maker the opportunity to produce a clean cut shank, which is desirable especially, in women's footwear today. However, when the shank is cemented to the shoe on the last, it insures that the shoe will then have the same perfect lines as are put in the arch of the last.

By sewing only the forepart of the shoe by the McKay or lockstitch method of sewing and cementing the shank, the operator is able to hold the shoe flat and thus control the original shape of the shoe and the fitting measurements.

In connection with the manufacture especially, of ladies' shoes, in order to help support the arch, it has been the practice to provide a bulge or offset on the inner side of the shank of the inner sole and termed a "cookie inner". It has never been proposed however to put this bulge or offset on the inside shank of the outersole, where on account of the much stiffer leather, a more adequate support is provided for the arch and weight of the body. If the shank of the shoe is sewed, on account of the curvature of the bulge, it would be difficult to channel and sew through such a shank. A further object of the invention therefore relates to the provision of the bulge or offset on the inside shank of the outersole of any type of shoe.

Still another object is to provide the innersole with a felt insert leaving the outer edge of the innersole intact and forming what I call a "ball cushion".

Referring to the drawing for a more complete disclosure of my invention,

Fig. 1 is a perspective view of a lady's shoe showing in dotted lines the sewing of the forepart of the shoe, and also in full lines the bulge or offset on the inside shank of the outersole.

Fig. 2 is a perspective view of the outer side of the molded leather sole with the bulge ready for application to the shoe,

Fig. 3 is a plan view of the inner side of the molded outersole shown in Fig. 2,

Fig. 4 is an elevation of the molded sole shown in Figs. 2 and 3,

Fig. 5 is a section on the line 5—5 of Fig. 1,

Fig. 6 is a section on the line 6—6 of Fig. 1,

Fig. 7 is a plan view of the innersole,

Fig. 8 is a section on the line 8—8 of Fig. 7.

The shoe is lasted in the customary manner of making McKay shoes in which, after the innersole 1 is correctly positioned on the last, the upper 2 and lining 3 are pulled tightly over the last and fastened to the under surface of the innersole by means of tacks 5 (or other used methods) which penetrate the innersole and are clinched against the steel bottom of the last. After the application of a steel shank stiffener 4 and filler 6, the shoe is then ready for laying the outersole.

The outersole 7 is provided with the offset or bulge 8 at the shank and is also channeled at 9 along the forepart of the sole only. The sole is molded into shape as shown in Figs. 3 and 4 and is then laid on the upper and held in place by the layer of cement 10 which has been applied to the outersole, temporarily adhering the sole to the forepart of the shoe and permanently adhering it to the shank of the shoe.

The last having been removed from the shoe, it is now sewed at 11 through the forepart of the sole with a McKay stitch, or lockstitch, or any other vertical method.

The channel 9 having been laid and the shoe beaten out, it is now ready for heelng.

One of the advantages of having the "cookie" on the outersole rather than on the innersole is that in the lasting, the upper lays in direct contact with the wood of the last at the shank, which is impossible when using a "cookie inner", unless using a special last with a depression to take up the thickness of the "cookie".

The general comfort of the shoe is improved by using the particular type of innersole with the ball cushion 12. It will be noted that the cushion extends to the inner side of the innersole but that the outer side 13 of the innersole is continuous and uncut. This outer portion 13 holds the general shape of the innersole, where as by cutting away the inner edge of the innersole and inserting the pad, the ball of the foot does not ride up on the hard part of the innersole. The material of the cushion may be any resilient material such as piano felt, rubber, etc., and may be held in place by sewing 14.

From the above description, it will be seen

that I provide a method of making shoes, that produces a shoe having the advantages of a machine sewed shoe and cemented shoe and by providing the outersole at the shank with 5 the bulge or "cookie", I make a shoe with a strong support for the arch and weight of the body.

While I have particularly illustrated and described the use of an outersole having the bulge 10 or "cookie" on the inner side, in connection with the manufacture of a lady's shoe where the forepart is sewed and the shank portion is cemented to the upper, I do not intend to so limit the use of this part of my invention. The same type of 15 shank can be applied to an all-over cemented shoe as well as to a sewed forepart-cemented-shank shoe. While it would be difficult with present machine methods to sew a shank to the upper having the bulge on the inner side, a 20 shank of such type would still have in such a shoe certain of the advantages, which are not present in the old and well known type of shank. While the bulge, on the shank of the outersole, is particularly advantageous in connection with 25 the type of ladies' shoes as disclosed, it is apparent the same could be used for shoes made in the men's, women's and children's field by other methods than that particularly described.

While I have illustrated and described the

present preferred form of the invention, it will be understood that I reserve the right to all changes properly falling within the spirit and scope of the appended claims.

5

I claim:

1. The method of making a shoe comprising providing an inner sole and an upper, assembling them on a last, lasting the upper and attaching its margin to the inner sole margin, providing an outer sole having a shank portion with 10 an offset on its inner side, pre-molding the offset to conform to the arch of the shoe, laying the outer sole with the pre-molded offset on the upper, securing the outer sole to the upper and comprising permanently cementing the shank 15 portion and offset of the outer sole to the upper.

2. The method of making a shoe comprising providing an inner sole and an upper, assembling them on a last, lasting the upper and attaching its margin to the inner sole margin, 20 providing an outer sole having a shank portion with an offset on its inner side, pre-molding the offset to conform to the arch of the shoe, laying the outer sole with the pre-molded offset on the upper, permanently cementing the shank 25 portion and offset of the outer sole to the upper and sewing only the forepart of the outer sole to the upper.

WARREN L. DELANEY.
